RECEPTACLE FOR SMOKING TOBACCO OR SIMILAR ARTICLE

Ralph T. Etzler, Columbus, Ohio

Application April 17, 1952, Serial No. 19,372

Term of patent 7 years

(Cl. D85—2)

To all whom it may concern:

Be it known that I, Ralph T. Etzler, a citizen of the United States, residing at Columbus, in the county of Franklin and State of Ohio, have invented a new, original, and ornamental Design for a Receptacle for Smoking Tobacco or Similar Article, of which the following is a specification, reference being had to the accompanying drawing, forming a part thereof.

Fig. 1 is a perspective view of a receptacle for smoking tobacco or similar article showing my new design;

Fig. 2 is a side elevational view thereof;

Fig. 3 is a top plan view thereof, to a reduced scale;

Fig. 4 is a rear elevational view thereof, to a reduced scale; and

Fig. 5 is a vertical sectional view thereof.

I claim:

The ornamental design for a receptacle for smoking tobacco or similar article, substantially as shown.

RALPH T. ETZLER.
